UNITED STATES PATENT OFFICE.

REYNOLD JANNEY, OF NEW YORK, N. Y.

COOLING AND WORK TABLE.

1,249,102.

Specification of Letters Patent.

Patented Dec. 4, 1917.

Application filed March 4, 1916. Serial No. 82,222.

To all whom it may concern:

Be it known that I, REYNOLD JANNEY, a citizen of the United States, residing at New York, in the county of New York and 5 State of New York, have invented certain new and useful Improvements in Cooling and Work Tables, of which the following is a specification.

This invention relates to a cooling and 10 work table. In certain processes, notably the gelatin reproducing process, it is necessary to spread a thin melted layer of composition over a surface, then cool this layer with as little evaporation as possible and 15 keep it cool while it is being used in the transfer process. It is difficult, particularly in warm weather to secure satisfactory results. It has been customary to keep an entire working room cooled to within the 20 required temperature limits. I provide a table which is simple in construction and of such character as to provide an easy and successful means for accomplishing the result stated irrespective of the temper- 25 ature or atmospheric conditions of the room or other place in which the work is being done.

In the drawings accompanying and forming part of the present specification I have 30 shown in detail one convenient form of embodiment of the invention which will be set forth fully in the following description.

Referring to said drawings:

Figure 1 is a top plan view of a table 35 involving my invention.

Fig. 2 is a similar view with the top and end top strips removed.

Fig. 3 is a longitudinal section on the line 3—3 of Fig. 2, looking in the direction of 40 the arrows but with the top in position.

Fig. 4 is a transverse section on the line 4—4 of Fig. 2, looking in the direction of the arrows and having the top in place.

Fig. 5 is a sectional detail on a larger 45 scale of a portion of the table.

Like characters refer to like parts throughout the several views.

The table comprises in its organization a box-like body such as that denoted in a 50 general way by 2, and a hollow top such as that designated in a general way by 3. The body 2 may be supported in any suitable manner as by the corner legs 4 and the intermediate and shorter legs 5.

55 Said body in the present case is open at the top and also at the front. The top

opening as shown is closed by the table top 3, and in the present instance the front opening is adapted to be closed by the fronts of several trays when the latter are 60 in the in positions thereof as will be herein-after more fully set forth. Said body comprises the duplicate ends or aprons as 6 adapted to be fastened in some suitable manner to the upper portions of the legs 65 and the back or rear apron 7 also fastened to the legs. I may if desired and as illustrated, fasten to the end apron 6 linings 8 of some proper insulating material such as asbestos, felt or ground cork, the linings 70 extending between the two pairs of corner legs 4. The bottom of the body is denoted by 9 and extends from one end apron 6 to the other and also abuts against the back apron or rear wall 7. The bottom may as 75 shown be lined as at 10 with suitable insulating material which may for instance be any one of those hereinbefore specified or anything else which will answer the desired purpose when required. Within the 80 body is suitably mounted the frame 9', this frame constituting a suitable support for the bottom or floor 9. The front of the body comprises the lower strip 11 and upper strip 12 fastened to the front corner legs 4. 85 I should note that the intermediate legs 5 abut at their upper ends against the bottom 9. The rear apron 7 and the lower strip 11 are fastened in some convenient manner to these intermediate legs. The strips 11 and 12 present practically the front of the body 2, the space between them constituting an opening for the introduction of articles into said box-like body 2, this being the front opening to which I have already alluded. As shown the end apron 6, the back apron 7 and the lower front strip 11 project somewhat below the bottom 9.

Within the body 2 and forming a part 100 thereof is the frame 13 of practically skeleton form. This frame may be connected to the corner or end legs 4 in any suitable manner. As shown it consists of two duplicate side bars and end and intermediate 105 cross bars connecting the said side bars, there being any suitable number of cross-bars. This frame presents a suitable support or carrier for the pan (hereinafter described) of the top 3, it being connected 110 in some convenient manner to the several corner legs 4.

The top 3 in superficial area corresponds virtually with that of the body in plan and is preferably hollow, so that it is adapted to receive a suitable cooling medium which 5 may be of any convenient nature, water cooled to the necessary temperature answering satisfactorily in this regard. As shown 10 the top consists of a pan 14 and a cover 15 therefor, both parts usually being made of metal and being riveted or otherwise suitably rigidly connected together along the upper marginal portion of the pan, the cover or plate 15 which constitutes the top proper of the table extending outwardly 15 beyond the margin of the pan. The top 3 is of such character as to provide for the circulation of the cooling agent therein, and the means whereby this particular condition is secured may be of any desired nature, the 20 partitions 16 arranged in staggered order in said hollow top meeting my requirement and being as will be inferred one of several ways by which the cooling substance can be circulated. Fitted into the pan, for instance at 25 one end thereof, is an inlet pipe as 17, while fitted into the pan at a diagonally opposite point is the outlet pipe 18, cold water or the like being supplied into the pan by the pipe 17, taking the course of the arrows in Fig. 1 30 and leaving the pan by way of the discharge or outlet pipe 18, the water circulating in the pan between the two pipes or ducts thus not only cooling the top 3 in an adequate manner but also the space in the body 2 35 below the pan.

The pan 14 is shown as sustained by the frame 13, the overhanging portion of the plate or cover 15 resting on filling pieces 19 united to the upper edges of the end aprons 40 or walls 6, back or rear apron 7 and upper front strip 12, the consequence being that when the top 3 is in operative position, it 45 closes the upper opening in the box-like body 2. Said body is adapted to receive within it means for removably supporting one or more composition coated elements and for this purpose one or more trays or shelves may be provided. I have shown several of such trays, each being denoted by 50 20. The end insulating linings 8 may as shown be provided with supporting and guide members as 21 to receive and support the respective trays. When said trays are closed as shown for example in Fig. 2, their 55 fronts are superimposed between the strips

11 and 12. As a result when the trays are in, the space within the body 2 will be closed. Said tray fronts may as shown be provided with pulls as 22. It will be perceived that there is considerable space or 60 interval between the uppermost tray or shelf 20 and the pan 14.

In using the table the following procedure may be adopted: Gelatin or other suitable composition is placed generally in a 65 thin layer on a suitable part such as sheet metal. The gelatin-coated pieces are placed on the shelves or trays 20 when the latter are out. The tray or trays which are out, are after the positioning of the gelatin-carrying parts, pushed in, so that the gelatin or the like on said plates can be cooled and the cooling action I might note, requires but little time. The flat metal top 70 of the table absorbs the heat from the plate 75 covered with the composition when this plate, with the said composition previously cooled, is placed on said table top, the consequence being that the composition is kept cool for as long as may be required in carrying 80 the reproducing process into effect.

The body 2 may be provided at its corners with the finishing plates 23 to cover the joints. I have described in detail a table suitable for my purposes and the idea in 85 being minute in description is to enable those skilled in the art to practise the invention. As will be clear, I do not restrict myself to any details.

What I claim is:

A cooling and work table having a hollow body open in the top and having an opening in the front, said body also having a frame therein below the upper edge thereof, a hollow top resting on the frame and comprising 95 a cover overlying the upper marginal edge of the body, a series of trays insertable through the front opening of the body, the trays having fronts which collectively close the front opening of the hollow body when 100 the trays are in, the upper tray being spaced from said hollow top and the latter having means for the entrance, circulation and discharge of a cooling substance.

In testimony whereof I affix my signature 105 in presence of two witnesses.

REYNOLD JANNEY.
